UNITED STATES PATENT OFFICE.

ISAAC L. PHILLIPS, OF NEW YORK, N. Y., ASSIGNOR, BY MESNE ASSIGNMENTS, TO VAN HEUSEN PRODUCTS, INC., A CORPORATION OF DELAWARE.

CUFF.

Application filed September 14, 1921. Serial No. 500,611.

To all whom it may concern:

Be it known that I, ISAAC L. PHILLIPS, a citizen of the United States, residing at New York city, in the county of New York, 5 State of New York, have invented certain new and useful Improvements in Cuffs; and I do hereby declare the following to be a full, clear, and exact description of the invention, such as will enable others skilled 10 in the art to which it appertains to make and use the same.

This invention relates to improvements in cuffs and particularly to soft folding cuffs which require no starch.

15 Ordinary soft cuffs are made up of a plurality of separate plies of relatively soft fabric so that the finished cuff has little inherent stiffness. In folding the cuff the outer layer or ply of fabric is subjected to 20 considerable strain because of the construction employed. The fabric at the edge of the fold where most of the wear comes is thus least capable of resisting wear and consequently the cuff quickly becomes frayed.

25 The object of the present invention is to avoid the difficulties mentioned and to provide an improved cuff, and means for attaching it to the shirt whereby the cost is reduced and a more satisfactory garment is 30 made available.

In accordance with the invention the cuff 35 is made of a multiple ply interwoven fabric, such as a two ply or three ply fabric or a two ply fabric interwoven with intermediate 40 filler threads. This fabric has a sufficient body to present a pleasing appearance and proper degree of stiffness without the aid of starch. The stiffness is retained permanently and the cuff does not therefore be- 45 come flimsy when in use as most soft cuffs do. A fabric such as that described does not fold readily and, in order to permit folding, it is preferably woven with a fold portion along a line of increased flexibility. Along this line the cuff will readily fold as is de- 50 sired in preparing the cuffs.

To permit the easy attachment of the cuff to the shirt and to provide for a finished edge which requires no binding and presents 55 the same appearance on both sides when the cuff is finished, the cuff is woven with the plies separated preferably at all of the four edges. The separated plies at one edge may thus be turned in and stitched to the sleeve

of the shirt while the plies at the remaining 55 edges are turned in and stitched to provide a finished edge.

The material may be woven in strips or sheets with alternating interwoven portions forming the body of the cuffs and separated 60 plies portions which when the cuffs are separated may be stitched in the manner described to provide the finished cuffs.

The several objects of the invention will be more clearly understood by reference to 65 the following specification and accompanying drawing in which:

Fig. 1 is a view in perspective of the finished cuff attached to the shirt sleeve,

Fig. 2 is a sectional view of the cuff and 70 shirt fabric shown in Fig. 1,

Fig. 3 is a view in elevation of the cuff material illustrating the separated plies at the edges thereof, and

Fig. 4 is a plan view of the fabric as it 75 comes from the loom.

The shirt 5 may be of any suitable material such as is customarily used in shirt manufacture. This is usually a thin fabric with little inherent stiffness. The cuff 6 is made of multiple ply interwoven fabric which because of its construction has the proper degree of stiffness. Preferably it otherwise matches the material of the body 80 of the shirt. The fabric illustrated is a two ply fabric with intermediate filler or gut thread layer. In the drawing the outer plies are illustrated conventionally at 7 and 8 and the filler threads at 9.

85 The cuff material as prepared has separated plies 10 at its upper edge and similar separated plies 11 at the remaining edges, the filler and interweaving threads being here omitted. At the folding line 12 the 90 filler and interweaving threads are similarly 95 omitted so as to provide a line of natural flexure upon which the material is readily folded to form the cuff.

100 As will be observed by reference to the drawing, the cuff is attached to the shirt sleeve by folding the separated plies 10 and stitching with the edge 13 of the sleeve fabric disposed therebetween. A neat and pleasing joinder of the cuff and shirt sleeve is thus accomplished. Before joining, the 105 remaining separated plies 11 may be folded in and stitched as indicated at 14 to provide the finished edge of the cuff which presents

the same appearance at both sides and may therefore be turned when soiled to present a fresh surface.

The cuffs illustrated are provided with 5 the usual button-holes 15 so arranged that they are in alignment when the cuff is folded on the line of flexure. The invention is adapted as well to the manufacture of non-folding cuffs, the structure and arrangement being identical with that described except for the omission of the line of flexure and the extra width of the folding portion. Even with a single thickness of multiple 10 ply fabric the cuff will have a pleasing and finished appearance more comparable to that 15 of a stiff cuff than to an ordinary soft cuff.

It will be particularly noted that the invention described avoids the necessity of binding strips or thickened edges resulting 20 from folding of the heavy fabric. The provision of the separated plies at the edges enables the production of a cuff with edges of not substantially greater thickness than the body of the cuff.

25 Various changes may be made in the structure and details of finish of the cuff without departing from the invention or sacrificing any of the advantages thereof.

I claim:

30 1. A cuff fabric composed of multiple
ply interwoven fabric having therein a series

of narrow longitudinal and transverse tubular portions which indicate the outline or edge portions of a plurality of cuff blanks and along which tubular portions the cuff 35 blanks are cut out; the main portions of the cuff blanks being multiple ply interwoven fabric and the tubular portions being of sufficient width to provide a divided edge suitable for edge binding purposes on each 40 of the cuff edges formed by cutting along the said tubular portions.

2. A multiple ply interwoven cuff fabric having therein a series of narrow longitudinal and transverse tubular portions 45 which form the long and end edges respectively of a plurality of cuff blanks, the said longitudinal tubular portions being spaced apart a distance equal to twice the width of a single cuff and a narrow zone or portion 50 of increased flexibility running parallel to the longitudinal tubular portions half way between each two consecutive tubular portions; the said transverse and longitudinal tubular portions being of sufficient width to 55 provide a divided edge on each of the edges of the cuff blanks formed by cutting along the said tubular portions.

In testimony whereof I affix my signature.

ISAAC L. PHILLIPS.
